Prof. S. Sprague

UNITED STATES PATENT OFFICE.

JAMES H. WHITING, OF FLINT, MICHIGAN.

WAGON.

SPECIFICATION forming part of Letters Patent No. 339,959, dated April 13, 1886.

Application filed December 17, 1885. Serial No. 185,954. (No model.)

To all whom it may concern:

Be it known that I, JAMES H. WHITING, of Flint, in the county of Genesee and State of Michigan, have invented new and useful Improvements in Wagons; and I do hereby declare that the following is a full, clear, and exact description thereof, reference being had to the accompanying drawings, which form a part of this specification.

10 This invention relates to certain new and useful improvements in the construction of what are ordinarily termed "farm" or "lumber" wagons, by means of which many of the features of the ordinary wagon are retained, 15 while all the objects to be derived from the shoulder-draft upon the axle are obtained.

The invention consists in the peculiar construction of the parts and their combination, all as more fully hereinafter described.

20 Figure 1 is a top plan view of my improved invention. Fig. 2 is a vertical longitudinal section.

In the drawings, A represents the axle, B the king-bolt, C the reach, and D the thimble-skein or boxes, all of the usual construction.

E are the hounds, which are bent in the form shown in Fig. 1 in rear of the axle from one piece. The side parts, F, of these hounds 30 are secured to the axle, and between the axle and the wooden sand-board G, near the shoulders of the axle, and from the front of the axle bend on curved lines toward each other and toward a common center, as shown at a, and 35 thence are bent directly forward parallel to each other, as shown at b, forming thereby an elongated bearing upon each side of the tongue H, which is pivotally secured between such parallel ends b by means of the bolt c. These 40 parallel front ends of the hounds must be sufficiently long to afford a firm bearing, such as has heretofore been had in tongues directly secured to the hounds by hounds or braces upon the rear end of the tongue itself.

I are draw-bars, the rear ends of which are 45 secured by means of clips d to the axle, near or on the inner end of the skein, while the front ends of said draw-bars I are secured to the sides of the box J, which is sleeved upon the tongue by means of bolts, clips, lugs e, or 50 otherwise, as may be deemed preferable. The bolt c, which pivotally secures the rear end of the tongue between the parallel sides of the hounds, passes through a longitudinal slot, h, in said tongue, and thereby allows the tongue 55 to slide backward or forward as you raise or lower it.

K is the hammer-strap, the rear end of which is pivotally secured by means of a bolt to the rear end of the sleeve or slide J, and the bolt 60 L forms the means for attaching the evener to the pole.

I am aware of the Patents No. 33,355 and No. 322,788, and make no claim to the constructions shown therein as forming part of 65 my invention.

I deem it important that the hounds E be formed of a single piece, as shown, as hounds so formed are more durable than those in which the ends back of the axle are joined by a cross-bar. 70

What I claim as my invention is—

In a wagon, the axle A, reach C, sand-board G, and king-bolt B, passing through said axle, reach, and sand-board, in combination with 75 the tongue H, having elongated slot h, the hounds E, terminating in parallel ends b, embracing said tongue, bolt c, passed through said ends and slot, draw-bars I, slide J, clips d, hammer-strap K, and bolt L, all constructed, 80 arranged, and operating substantially as described.

JAMES H. WHITING.
